United States Patent Office

Des. 225,724
Patented Jan. 2, 1973

225,724

BOTTLE

Gordon A. Strand, Toledo, Ohio, assignor to Owens-
Illinois, Inc., Toledo, Ohio

Filed Oct. 12, 1971, Ser. No. 188,642

Term of patent 7 years

Int. Cl. D9—01

U.S. Cl. D9—39

FIG. 1

FIG. 3

FIG. 2

FIG. 5

FIG. 4

FIG. 1 is an elevational view of a bottle showing my new design;

FIG. 2 is a top plan view;

FIG. 3 is an elevational view looking from the right of FIG. 1;

FIG. 4 is an elevational view looking from the left of FIG. 1; and

FIG. 5 is a fragmentary sectional view taken on line 5—5 of FIG. 1.

The side opposite that seen in FIG. 1 is a mirror image of the side shown.

I claim:

The ornamental design for a bottle, substantially as shown and described.
